C. W. COLE

BURGLAR ALARM AND LIMITED MOVEMENT LOCK FOR DOORS

Filed Jan. 28, 1926

INVENTOR.

C. W. COLE

BY

P. F. Galliher

ATTORNEY.

UNITED STATES PATENT OFFICE.

CLEVELAND WALTER COLE, OF DENVER, COLORADO.

BURGLAR ALARM AND LIMITED MOVEMENT LOCK FOR DOORS.

Application filed January 28, 1926. Serial No. 84,301.

This invention relates to devices, for attachment to doors, which give an audible indication that the door is being opened.

The principal object of the invention is to provide a device of this character which will not only give an audible indication that an attempt is being made to open the door, but will prevent the door from being opened.

A further object is to provide means in a device of this character which will, if desired, allow the door to be opened to a limited predetermined degree.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is an elevation of the invention attached to a door and the casing thereof.

Fig. 2 is a plan view of the same.

Fig. 3 is an end elevation of the alarm device.

Fig. 4 is a detail view of the chain attachment link.

The invention comprises a frame 10, semi-circular in shape, and having a flat base portion 11. A spring actuated alarm bell 12, controlled by a trigger 13, is carried on the base 11, within the frame 10. The frame 10 is designed to be secured to a door, indicated at 14, by means of suitable screws 15. Extending across the semi-circular portion of

the frame 10, is a long slot 16 communicating at one extremity, by a cross passage 17, with a relatively short slot 18. The trigger 13 of the bell 12 is arranged directly under and adjacent the extremity of the short slot 18.

Secured to the door casing, indicated at 19, by means of screws 20, is a plate 21, to which a chain 22 is secured. The chain 22 terminates in a key 23, illustrated in detail in

Fig. 4. This key is secured to the end link of the chain 22, and has its extremities oppositely extended, forming feet 24. The chain 22 is only of a length sufficient to allow the key 23 to be inserted in the cross passage 17 of the frame 10, when the door is

closed. The key then may be brought into alignment with either the long slot 16 or the short slot 18, with its feet 24 engaging the under sides of the slot edges.

Let us assume that the key 23 is in alignment with the short slot 18. Any movement of the door will now cause the key to move into the slot 18, where it will contact with the trigger 13 of the bell 12, thus causing the trigger to release the bell mechanism so as to give an audible alarm that an attempt is being made to open the door. The key will then contact with the end of the short slot 18 and prevent the door from being opened. The short slot 18 is of a length which will allow the door to be moved approximately an eighth of an inch, so as to prevent an intruder from seeing past the door.

Should the occupant of the house or room, in which the device is installed, desire to interview the intruder without allowing him to enter, the key 23 is passed, through the cross passage 17, into alignment with the long slot 16. The door may now be partially opened which will cause the key to travel across the semi-circular frame 10 the length of the long slot 16. The slot 16, however, when the key has reached its extremity, will prevent further opening of the door. The length of this slot is such as to allow the door to open approximately six inches, through which opening, the intruder may be interviewed but his entrance is absolutely barred since it is impossible to remove the key without closing the door. When not in use, the key is removed from the frame 10 and allowed to hang upon its chain at the door casing.

The bell 12 may be any of the usual spring actuated bells such as employed for press button door bells and the like. The mechanism for ringing the bell forms no part of the present invention and, since any trigger actuated mechanism would serve the purpose, further description thereof is deemed unnecessary.

While a specific form of the improvement has been described and illustrated herein, it is desired to be understood that the same may be varied, within the scope of the appended claims, without departing from the spirit of the invention.

Having thus described the invention, what

I claim and desire secured by Letters Patent
is:—

1. A device adapted to give an audible signal upon opening a door and to limit said opening, comprising a semi-circular frame having a relatively long slot and a relatively short slot formed therein; said slots communicating with each other; a trigger arranged adjacent said short slot so as to release an alarm mechanism; a flexible co-acting member; a key carried by said flexible member and arranged to detachably engage either of said slots and travel therein.
2. A device adapted to give an audible signal upon opening a door and to limit said opening, comprising a semi-circular frame

having slots formed therein a base arranged to be attached to said door; and support said frame a bell carried within said frame; a trigger operatively connected to said bell; means arranged to be secured to the casing of said door and to detachably engage said frame so as to actuate said trigger at predetermined positions of said door, said means comprising a plate secured to 25 said casing; a chain secured to said plate; and a key carried on the extremity of said chain and arranged to travel in said slots in said frame.

In testimony whereof, I affix my signature.

CLEVELAND WALTER COLE.
